UNITED STATES PATENT OFFICE.

THOMAS M. BRINTNALL, OF KANSAS CITY, MISSOURI.

SAFE.

SPECIFICATION forming part of Letters Patent No. 292,155, dated January 22, 1884.

Application filed January 19, 1883. (No model.)

To all whom it may concern:

Be it known that I, THOMAS M. BRINTNALL, of Kansas City, in the county of Jackson and State of Missouri, have invented certain new and useful Improvements in Safes; and I do hereby declare the following to be a full, clear, and exact description of the invention, such as will enable others skilled in the art to which it pertains to make and use the same.

10 My invention relates to an improvement in burglar-proof safes, the object being to produce a safe peculiarly adapted, by reason of its novel form and structure, to resist a forced entrance.

15 With this object in view my invention consists in certain details of construction and combinations of parts, as will be hereinafter described, and pointed out in the claims.

In the accompanying drawings, Figure 1 is 20 a view in perspective of a safe embodying my invention. Fig. 2 is a rear view thereof. Fig. 3 is a view in side elevation. Fig. 4 is a view in vertical longitudinal section. Fig. 5 is a 25 detached view of one of the corrugated cast-steel rings. Fig. 6 is a sectional view, showing two of the structural modifications of which the invention is susceptible. Fig. 7 is a view in side elevation, showing a modified arrangement for uniting the two parts of the safe; and 30 Fig. 8 is a similar view of a safe composed of three parts or sections, instead of two, as shown elsewhere.

A and B respectively designate the two parts of a cylindrical safe constructed in accordance 35 with my invention, the open ends of said parts having the same cross-section and being adapted to be secured together, as will be hereinafter described. In structure the said parts are composed of interlocking chilled cast-steel 40 rings and composite ends. The outer edges of the opposite faces of the said rings, which are designated by C, are corrugated, whereby the rings are interlocked when bolted together. The bolting of the rings may be effected in several 45 different ways, the preferred method being to provide the plain inner edges of the rings with bolt-holes D, conical bolts E, composed of twisted iron and steel, and having soft riveting ends, being inserted in the alternate holes. In length the bolts are adapted to extend through and a little beyond the unoccupied holes of the next adjoining ring, the

projecting ends of the bolts being upset, as shown in the drawings.

The ends of the parts A and B are composed 55 of chilled steel disks F, having two disks, G, of lesser diameter, secured in any suitable manner to their inner faces. The edges of the inner faces of the disks F are provided with corrugations, arranged to interlock with the corrugated surfaces of the outer face of the ends of most of the rings, the inner peripheries of said rings being provided with dovetails G', which fit into suitable mortises, H, formed in the peripheries of the disks G. The part A of the 60 safe is rigidly secured to a standard, I, supported upon a suitable bed, J, by means of set-screws K, which are manipulated as necessary to elevate or depress the standard and part A, and thus compensate for any loss of adjustment 65 between the two parts of the safe. The part B of the safe is supported by and adapted to be rotated on its transverse axis in a carriage, L, which is provided with anti-friction rollers M, to facilitate such manipulation. The said part 70 B of the safe is prevented from lateral displacement in its carriage, and also rendered of easier operation by providing its end with a short journal, N, which is supported in a suitable bearing in the upper end of an arm, O, forming 75 an upright extension of the carriage L, which is provided with three swiveled rollers, P. The two parts of the safe are united by means of a hinge, U, the outer ends of the 80 leaves of which are respectively hinged to their supports in the manner shown, the lower end of the pintle V of the hinge extending into a slot, W, formed in the bed J.

In virtue of this mode of uniting the two parts of the safe a very mobile connection between 85 them is obtained, and one that allows the part B to be easily handled in opening and closing. The chambers X of the parts A and B are closed by means of circular doors Y, which may be solid or composite in structure, both constructions being shown in Fig. 4 of the drawings. These doors are supported in bearings Z, formed by increasing the transverse sections of such of the rings C as are located at the desired distance from the open ends of the 90 said parts. Instead, however, of modifying certain of the rings C, as described and shown, independent ring-bearings inserted in the open 95 ends of safe and adapted to support the safe-

doors may be employed. Rings A', having their inner peripheries divided into equidistant segments B', are attached to the modified rings C in such position that the said segments project into the apertures which receive the doors Y, the inner faces of the same being provided with outwardly-extending segments C', corresponding in size and relative arrangement to the segments B'. If desired, the segments B' 5 may be formed integral with the bearings Z, and as for the segments C', they may be formed integral with the doors or with disks secured to their inner faces, according as the doors are solid or composite in structure.

15 The operation of locking the doors within their bearings consists in registering the segments C' with the spaces between the segments B'. This done, the doors are seated in their bearings and sufficiently rotated by their handles E' to engage the segments, being locked when such engagement is effected by means of suitable combination-locks, F', with which time mechanism is preferably associated, although none is herein shown. The said safe- 20 doors are removed and replaced by means of carriers G', which also fulfill the function of supporting the doors while being rotated for the purpose of engaging or disengaging the said segments. The outer ends of the carriers 25 are provided with perforations H', adapted to receive studs I', formed integral with or attached to the doors, and with pivotal hooks J', which lock the doors and carriers together by engaging with grooves K', formed in the outer 30 ends of the studs. The inner ends of the carriers aforesaid are pivoted to leaves L', hinged to bearings M', adapted to be vertically adjusted to compensate for any loss of adjustment between the carriers and the safe-doors.

35 The said bearings are attached to the parts A and B of the safes and guided in their adjustments by means of guides N', formed with or attached to the rings C, and adapted to fit into grooves N'', formed in the inner faces of the 40 bearings, which are adjusted by set-screws O', mounted in lugs P', located below them. Screws Q', mounted in lugs R', situated above the bearings, are arranged to be impinged on their upper edges, and thus prevent them from 45 being displaced vertically. The parts A and B are secured together by substantially the same devices as are employed to lock the safe-doors in their bearings, the segments S' of a ring, T', set into part A being arranged to be 50 engaged with the segments U' of a flanged ring, V', attached to the annular extension W' of the part B, said extension being adapted to fit within a suitable recess, X', formed in the part A.

55 The operation of securing the two parts together consists in registering the segments U' of the ring V' with the spaces between the segments S' of the ring T', and then seating the extension W' in the recess X'. This done, the 60 part B is rotated on its transverse axis by its handle Y', to engage the segments with each other. When the two parts of the safe are

thus locked, the corrugated faces of the outermost of the rings C of each part will interlock and prevent the application of appliances for 70 forcing the safe open at this point. The parts A and B are maintained in their locked adjustment by means of a combination-lock, Z', which may or may not have time mechanism associated with it.

75 The structural character of a safe embodying my invention admits of the careful chilling of the several parts before they are put together, and when united the interlocking of the contiguous parts is a safeguard against the 80 entrance of appliances of whatever character for forcing an entrance into the safe. Should an effort to force the parts of the safe open be successful, it still remains to violate the doors to gain admission to the valuables contained 85 in the compartments provided to receive them.

It is apparent that one or all of the features of novelty in my improvement may be modified within certain limits.

90 Two of the structural modifications of which the invention is susceptible are illustrated in Fig. 6 of the drawings, in which one part of a cylindrical safe, embodying end and rings, is shown. The said modified end consists of two interlocking disks, A'', secured to the rings 95 B'' by bolts C'' and D'', which also fulfill the function of binding the rings together. The said bolts are respectively attached to the disks and to the ring which forms the bearing for the door, the inner ends of the bolts being 100 connected by right and left hand nuts E'', by means of which the bolts are drawn together with the effect of uniting the rings, and also of holding the disks in place.

105 The modified arrangement of uniting the two parts of the safe, which is shown in Fig. 7 of the drawings, consists, essentially, in forming a lug, F'', with one part of the safe, and a similar lug with a band, G'', encircling the outer end of the other part thereof, and 110 made integral with or attached to the standard of such part, the said band being arranged to extend beyond the line on which the two parts join.

115 In locking or unlocking a safe of this type the part encircled by the band is rotated within the same to effect the engagement or disengagement of the locking devices, as the case may be. To open the safe the part encircled by the band is swung aside, being supported 120 in such movement by the band.

125 The safes shown in the drawings are cylindrical in contour; but this is not a structural necessity, for they may be varied in form to include the spherical, octagonal, hexagonal, and square; but whatever be the form of parts their open ends should conform in cross-section.

130 It is also apparent that one part of a safe may be made so shallow as to contain no chamber for the reception of valuables, the function of a part so constructed being simply to conceal and protect the door of the other part.

Instead of mounting one part of the safe on

a stationary and the other on a movable support, both parts of the safe may be mounted on movable supports, as shown in Fig. 8 of the drawings, their ends being united to the 5 opposite faces of a ring, H^2 , supported between the two parts and adapted to be rotated on its axis.

In view of the modifications herein suggested and also those of which the invention 10 is obviously susceptible, I would have it understood that I do not limit myself to the exact construction shown and described, but hold myself at liberty to make such changes and alterations as fairly fall within the spirit 15 and scope of my invention.

Having fully described my invention, what I claim as new, and desire to secure by Letters Patent, is—

1. A safe, consisting of two or more parts 20 whose open ends are constructed similarly in cross-section, and provided with interlocking means, one of said parts being adapted to partially rotate, whereby said ends are fitted together and securely locked, substantially as 25 set forth.

2. A safe consisting of two parts, each having a chamber to receive valuables, said parts being constructed to closely fit together and be securely interlocked by a partial rotation 30 of one of said parts, substantially as set forth.

3. The combination, with a safe consisting of two parts, each having a chamber to receive valuables, of segments arranged within and without the respective parts, and adapted 35 to be interlocked by the partial rotation of one of said parts to lock the parts together, substantially as set forth.

4. A safe consisting of two parts mounted upon independent standards, one of which is 40 stationary and adjustable, while the other standard is adapted to be moved when the parts of the safe are joined, substantially as set forth.

5. The combination, in a safe, of two parts 45 adapted to be interlocked with independent hinged standards, one of said standards having rollers upon which it moves, and each carrying the respective parts, substantially as set forth.

50 6. The combination, with a safe consisting of two parts, of independent standards connected by a hinge whose pintle projects into a slot formed in a supporting-bed, substantially as set forth.

55 7. The combination, with a safe consisting of two parts, closed at one end and open at the other, adapted to have their open ends secured together, and respectively provided with a chamber to receive valuables, of doors 60 located within the said parts and arranged to close their respective chambers, substantially as set forth.

8. In a safe, the combination, with a removable door, of a hinged carrier supported upon the safe and adapted to be attached to 65 and detached from the door, substantially as described.

9. The combination, with a safe consisting of two parts, the ends of which are adapted to be secured together, each part having a 70 chamber to receive valuables, of circular doors for said chambers, and carriers supported upon the safe and adapted to be attached to the doors when the safe is open and to be detached from them when the same is closed, 75 substantially as set forth.

10. The combination, with a safe consisting of two parts, the open ends of which are adapted to be secured together, each part having a chamber to receive valuables, of circular doors for said chambers, carriers supported upon the outside of each part, adapted to be attached to the doors when the safe is open and to be detached from them when the same is closed, and means for adjusting the 85 carriers, substantially as set forth.

11. A safe-body composed of a series of rings, each made in a single piece, and provided with interlocking contiguous surfaces, and bolts for securing the rings together, 90 substantially as set forth.

12. A safe composed, essentially, of a series of united rings, the outer edges of the opposite faces of which are corrugated, the inner edges of the rings being provided with 95 transverse holes, which receive the bolts by which the rings are united, substantially as set forth.

13. The combination, with a safe-body consisting of a series of rings, of a disk or disks 100 secured to said body to form one end of the safe, and a suitable door, substantially as set forth.

14. The combination, with a series of united rings, the opposite faces of which are corrugated and interlocked, the inner periphery of the endmost ring being provided with a dovetail, of a disk having the edge of the inner face arranged to interlock with the corrugated outer surface of the endmost ring, and two 110 disks secured to the inner face of the disk aforesaid, their peripheries being mortised to receive the dovetail of the endmost ring, substantially as set forth.

In testimony whereof I have signed this 115 specification in the presence of two subscribing witnesses.

THOMAS M. BRINTNALL.

Witnesses:

GEORGE COOK,
GEORGE F. DOWNING.
